US00D516954S

(12) United States Design Patent (10) Patent No.: **US D516,954 S**
Essig (45) Date of Patent: **** Mar. 14, 2006**

(54) **SURFACE CONFIGURATION OF A FRONT
PORTION OF A GOLF CART AND/OR
REPLICAS THEREOF**

D498,704 S * 11/2004 Bonner et al. D12/16

* cited by examiner

(75) Inventor: **Hardy Essig**, Rutesheim (DE)

Primary Examiner—Stacia Cadmus
(74) Attorney, Agent, or Firm—Crowell & Moring LLP

(73) Assignee: **Dr. Ing. h.c.F. Porsche
Aktiengesellschaft**, Stuttgart (DE)

(57) **CLAIM**

(**) Term: **14 Years**

The ornamental design for a surface configuration of a front portion of a golf cart and/or replicas thereof, as shown and described.

(21) Appl. No.: **29/231,032**

DESCRIPTION

(22) Filed: **Jun. 1, 2005**

(30) **Foreign Application Priority Data**

Dec. 2, 2004 (EM) 000262738

(51) **LOC (8) Cl.** **12-02**

(52) **U.S. Cl.** **D12/16**
